Specification of Letters Patent. Patented Mar. 20, 1917.

Application filed June 21, 1916. Serial No. 104,843.

To all whom it may concern:

Be it known that we, MAYNARD LOOMIS and PAUL M. LOOMIS, citizens of the United States, residing at Orting and Puyallup, respectively, in the county of Pierce and State of Washington, have invented certain new and useful Improvements in Gates, of which the following is a specification.

This invention relates to improvements in gates, and the object of this improvement is to provide a rolling gate of strong and simple form of construction, together with efficient mechanism whereby said gate may be operated by a person at a distance therefrom so that when a person in a vehicle or on horseback approaches the gate, he will not have to get out of the vehicle or dismount to open and close the gate.

The invention consists in the novel construction of gate operating and supporting means, and the adaptation and combination of such means with a gate, as will be more clearly described in the following specification, illustrated in the accompanying drawings and finally pointed out in the appended claim.

In the drawings, Figure 1 is a view in elevation of a gate embodying this invention as it may appear when closed, certain parts being shown in cross section; Fig. 2 is a similar view of the gate in an open position; Fig. 3 is a view in vertical section on broken line 3—3 of Fig. 1; Fig. 4 is a view in sectional elevation of a gate post on broken line 4—4 of Fig. 1 with the gate removed; Fig. 5 is a view partly in section and partly in elevation illustrating the method of forming the corners of the gate; Fig. 6 is an enlarged plan view of the gate-operating mechanism showing certain parts in cross-section on broken line 6—6 of Fig. 1; Fig. 7 is an enlarged view in cross-section on broken line 7—7 of Fig. 2, and Fig. 8 is a view in perspective of a detail of the invention.

Referring to the drawings, throughout which like reference numerals indicate like parts, the numeral 10 indicates a gate preferably consisting in a tubular frame 11 having intermediate cross-bars 12 and longitudinally extending wires or stays 13. The upper corners of the gate 10 are preferably joined by cutting them on an angle of substantially forty-five degrees, as indicated by the line 14, inserting a right-angularly

shaped corner piece 15 therein, and securing with rivets 16 as more clearly shown in Fig. 5.

The lower corners of the gate may be joined by an elbow coupling 17 of well-known form, the above described method of construction producing a strong and rigid frame that is easily assembled.

In mounting the gate I provide three specially constructed upright posts 18, 20 and 21 that are secured to a horizontal bed-piece 22 which is preferably embedded or partially embedded in earth or concrete, as indicated in Figs. 1 and 2.

The posts 20 and 21 are each of two-part construction and the two parts are spaced apart by the bed-piece 22 and by top cross-pieces 23 and 24 respectively, (see Fig. 3) sufficiently to permit the gate to move endwise therebetween. The post 18 is recessed, as at 25, for the reception of the forward end of the gate to prevent lateral displacement thereof, the recess 25 being enlarged, as at 26, for the reception of the elbow 17, and forming shoulders 27 with which the top portion of the elbow may engage, to prevent lifting of the forward end of the gate when such gate is closed.

The bottom bar 12 of the gate is provided with downwardly projecting brackets 28 within which are journaled grooved wheels or rollers 30 that are adapted to support the gate and to roll on a rounded track 31 that extends lengthwise of the bed-piece 22.

The operating mechanism for the gate 90 consists in a link 32 having one end articulated by pivot 33 with a bracket 34 on the top gate bar 12, and the other end articulated by pivot 35 with the ends of two short links 36 that are articulated by pivots 37 with the outer ends of two longer links 38 that have their inner ends pivotally connected by pivots 39 with the opposite inner sides of the two parts of the post 20, as shown in Fig. 6, in such manner that the link 32 is free to pass between the two links 38 and the two links 36.

40 is a clip that is placed upon the pivot 35 and has two operating cables 41 and 41¹ connected therewith, the cables passing upwardly between vertical rollers 42 mounted in the tops of the post 20, thence outwardly in opposite directions over horizontal rollers 43 to points along the roadway (not shown) where they may be reached and 110

pulled by persons in a vehicle that is approaching or leaving the gate from either side.

The top of each member of the post 20 is recessed as at 44, for the reception of the rollers 42 and 43 and each of such members is provided on its outside surface with an ornamental plate 45 through which the cable 41 or 41¹ passes outwardly.

10 The bottom rail 12 of the gate is provided at a point just in front of the foremost bracket 28 with a fixedly secured track cleaner 46, see Fig. 8, having a notch 47 in the bottom end thereof that fits over the 15 track 31 and serves to remove dirt, snow and the like therefrom as the gate is moved back and forth.

A cross-bar 48 is preferably placed under the bottom of the post 20 and angular braces 20 50 are inserted between this cross-bar and the opposite sides of the post 20 to brace such post against sidewise tension exerted by the cables 41 and 41¹. 51 is a fence wire that may be secured to the posts 18 and 21, as indicated, to form a fence.

The gate, when closed, assumes the position shown in Fig. 1, with the links 32, 36 and 38 resting on the top bar of the gate and slightly out of alignment so that the 30 pivots 35 and 37 are slightly below the center line that passes through the pivots 33 and 39 and the gate is thereby locked in a closed position. When a pull is exerted on either of the cords 40 or 41 the links 32, 36 35 and 38 are lifted and an endwise pull is exerted on the gate, causing it to move along the track 31 from the closed position shown in Fig. 1 to the open position shown in Fig. 2, the links passing between the two side 40 members of the posts 20 and 21 respectively, and the link 32 passing between the two links 36 and the two links 38 and all of such links assuming a locking position on the top bar 12 of the gate and on the opposite 45 side of the post 20 in a manner already described, and locking the gate in an open position.

The starting movement of the gate from an open or closed position is accomplished by a toggle action of the links 32, 36 and 38 whereby a relatively great leverage is obtained to overcome inertia but after the gate has started to move the link 32 will be moved substantially into alignment with the cable 41 or 41¹, thereby giving a direct 55 pull and permitting sufficient speed to be imparted to the gate to carry it past the medial position to a completely open or closed position as the case may be.

The shorter links 36 that connect the main 60 toggle links 32 and 38 form a more flexible pivot and admit of a more free and easy movement of the links than would be secured by pivoting the links 32 and 38 directly to each other.

65 What we claim, is—

A gate comprising a rectangular frame formed of metal pipe and having its lower corners joined by elbow couplings, rollers on said frame, a trackway for said rollers, a vertical guide post for the rear end of said gate, a two-part vertical support disposed medially of the distance through which said gate may move, and extending above the top of said gate, rollers mounted in the top of 70 said support, a link pivoted to said gate, links pivoted to said support, short links articulating said first-named links with said last named links, cables connected with said shorter links, said cables passing upwardly 80 over said rollers in the top of said support, and thence outwardly therefrom in opposite directions, and a recessed post for the forward end of said gate, said post having shoulders that engage with said elbow couplings to prevent vertical movement of said gate.

75 Signed at Seattle, Washington, this 14th day of June, 1916.

MAYNARD LOOMIS.
PAUL M. LOOMIS.
